(57) **CLAIM**

I claim the ornamental design for a link for a lifting device, as shown and described.

DESCRIPTION

This application is directed to a link for a lifting device as described in commonly-owned U.S. application Ser. No. 14/445,253, filed Jul. 29, 2014, the contents of which are incorporated herein by reference in their entirety.

FIG. 1 is a perspective view from the top, front, and right side of a link for a lifting device showing the new design.

FIG. 2 is a front view thereof. The rear view is a mirror image of the front view.

FIG. 3 is a top view thereof.

FIG. 4 is a bottom view thereof.

FIG. 5 is a left side view thereof.

FIG. 6 is a right side view thereof.

FIG. 7 is a cross-sectional view thereof, taken along the line FIG. 7-FIG. 7 of FIG. 3; and,

FIG. 8 is a cross-sectional view thereof, taken along the line FIG. 8-FIG. 8 of FIG. 3.
